(57) **CLAIM**

We claim the ornamental design for a bottle cap, as shown and described.

DESCRIPTION

FIG. 1 is a top, front perspective view of a bottle cap, showing our new design;

FIG. 2 is a bottom, front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an exploded top, front perspective view thereof.

(Continued)

The broken lines shown in the drawings indicate portions of the bottle cap that form no part of the claimed design.
